TIME REMINDER

Thomas Hewitt, 5842 SW. 30th St., Miami 55, Fla.

Filed Mar. 13, 1959, Ser. No. 799,153

4 Claims. (Cl. 116—133)

This invention relates to attachments for timepieces and more particularly to a device to remind the user of the timepiece of a time of day or night.

Although the attachment for the timepiece may be used for numerous purposes, one practical use of the reminder is to enable a person to know at a glance how much time remains for legally occupying a parking space that has a meter associated with it. It is evident, though, that other time periods may be indicated by the use of the same attachment.

One of the objects of the invention is to provide an attachment for a timepiece, principally a wrist watch since they are more commonly used at the present time, requiring no alteration to the watch nor mechanical fasteners such as screws to retain the attachment in place. Instead, the attachment is specially designed so that it clips under the pins of the watch used to hold the strap fastened to the case of the watch. Further, the timepiece face is essentially unobstructed since the attachment may be made of a neat thin strip of clear plastic so that the numerical designations on the face of the watch and the hands are visible by inspection through the body of the attachment.

In order to be practical the watch attachment is made of very simple construction and furthermore, the adjustment of the reminder is achieved very easily, preferably by turning a finger wheel which is superposed beneath the body of the attachment that is, between the watch crystal and the attachment body. The hand wheel has a neat, thin line scribed or otherwise applied thereon to be used as a time reference.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary top view of a watch and strap which has the attachment applied thereto.

Figure 2 is a top view of the attachment in Figure 1.

Figure 3 is a plan view of the attachment in Figure 2.

Figure 4 is a longitudinal sectional view taken approximately on the line 4—4 of Figure 1 and showing the watch in elevation.

In the accompanying drawings there is shown watch 10 with watch strap 12 having end loops 14 and 16 held fastened to the case of the watch by means of conventional pins 18 and 20 carried in openings in the projecting ears of watch 10. The watch is selected for illustration because wrist watches are most generally used and the principal application of the invention is, therefore, in connection with wrist watches. However, it is evident that the principles of the invention are applicable in connection with other types of timepieces.

Attachment 22 is constructed of an elongated support or base 24 narrower than the face of the watch 10 and

2

made of transparent plastic material so as to enable the user of the watch to see the hands and numerals of the watch when the base is attached to the watch case. Base 24 has an essentially flat center section 26, downwardly bent ends 28 and 30 integral with the center section and connected therewith by smoothly curved corners. Attachment tabs 31, 32, 34 and 36 protrude laterally from ends 28 and 30. The tabs cooperating with ends 28 and 30 form laterally outwardly opening pockets 27, 29 which accommodate pins 20 and 18 together with the loops 14, 16 of the strap 12 that are fastened on the attachment pins 18 and 20. The selection of plastic for the attachment is such that the attachment base 24 has sufficient inherent resilience to enable it to be transversely bent so that tabs 31 and 32, for instance, may be slipped under the loop 14 fastened on the pin 20 and tabs 34 and 36 slipped under the loop 16 fastened on the pin 18, after which the inherent resilience of the base will return the base to its normal position with the pockets 27, 28 receiving the loops 14, 16 and said ends 28, 30 fitting between the loops 14, 16 and the watch 10 and under said loops 14, 16 to detachably hold the base in place on the watch case. Alternatively, the plastic from which the base is made may be quite rigid, but this would have the disadvantage of requiring pins 18 and 20 to be removed so that the base may be fitted over the face of the watch after which the pins 18 and 20 are replaced.

The side edges of base 24 have laterally opening finger receiving recesses 40 and 42. These are preferably smoothly curved for neatness of appearance. A finger operated wheel 44 having a serrated periphery 46, is mounted for rotation beneath the center section 26 of base 24. Wheel 44 is transparent and has a time reference marker 48 applied thereon in any manner, for example it may be scribed and/or painted or otherwise formed. Wheel 40 is of a large enough diameter so that portions of periphery 46 project into the areas attended by the recesses 40 and 42 at all times. The means mounting the wheel for rotation are capable of a number of modifications, one of which is a rivet 50 which extends through aligned openings in the center of section 26 and wheel 44.

In use, the wheel 44 is turned until the marker 48 designates a particular time reference over the face of the watch. Sufficient friction exists between wheel 44 and the center section 26 of base 24 so that the wheel 44 will not inadvertently be moved after it is manually set. The user of the watch and attachment has a time reference made by the position of the marker 48 over the face of the watch.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the invention as claimed.

60. What is claimed as new is as follows:

1. An attachment for a watch comprising an elongated base narrower than a face of a watch and adapted to extend across a face of a watch, said base having ends bent downwardly and provided with outwardly extending tabs adapted to be inserted downwardly between a watch and wrist strap loops fastened to said watch by retaining pins and whereby to detachably attach said base to a watch, a transparent wheel beneath said base adapted to overlie a face of a watch in the center thereof, means rotatably mounting said wheel on said base, and a marker on said wheel for registration with selected grad-

uations on a watch face to indicate a selected time marking on a watch face.

2. An attachment according to claim 1, said downwardly bent ends and tabs forming outwardly and upwardly opening pockets on the ends of the base adapted to receive therein wrist watch end loops fastened by retaining pins to a watch.

3. An attachment according to claim 1, said base having side edges provided with finger receiving recesses therein above said wheel to facilitate rotating said wheel by the fingers of a hand.

4

4. An attachment according to claim 3, said base being transparent to render a watch face visible below said base.
